VACUUM CLEANER CLEANING ATTACHMENT FOR WALL CONVECTOR RADIATORS OR THE LIKE

Henry F. Bearse, Box 223, Yarmouth Port, Mass., and
Edgar Bearse II, Corporation Road, Dennis, Mass.

Filed Sept. 22, 1965, Ser. No. 87,117

Term of patent 14 years

(Cl. D9—2)

FIG. 1 is a front perspective view of a vacuum cleaner cleaning attachment for wall convector radiators, or the like, showing our new design;

FIG. 2 is a top view thereof; and

FIG. 3 is a bottom view thereof.

The side not shown has substantially the same appearance as the side shown.

We claim:

The ornamental design for a vacuum cleaner cleaning attachment for wall convector radiators or the like, as shown and described.
